(57) **CLAIM**

The ornamental design for a handle for a non-electric tool, as shown and described.

DESCRIPTION

FIG. 1 is a perspective view of a handle for a non-electric tool showing my design;

FIG. 2 is a front elevational view thereof, the rear elevational view being a mirror image thereof;

FIG. 3 is a left elevational view thereof;

FIG. 4 is a right elevational view thereof;

FIG. 5 is a top plan view thereof; and,

FIG. 6 is a bottom plan view thereof.
